UNITED STATES PATENT OFFICE.

CARL HENDERSON, OF OAK PARK, ILLINOIS, ASSIGNOR TO MIEHLE PRINTING PRESS AND MANUFACTURING COMPANY, OF CHICAGO, ILLINOIS, A CORPORATION OF ILLINOIS.

SHEET-DELIVERY APPARATUS.

973,428.

Specification of Letters Patent. Patented Oct. 18, 1910.

Application filed May 13, 1909. Serial No. 495,599.

To all whom it may concern:

Be it known that I, CARL HENDERSON, a citizen of the United States, residing in Oak Park, in the county of Cook and State 5 of Illinois, have invented a new and useful Improvement in Sheet-Delivery Apparatus, of which the following is a specification.

This invention is an improvement in the sheet delivery apparatus of printing presses. 10 The main feature of it is found in the means adopted for propelling the sheet. These means consist of two pairs of opposing tapes, each pair gripping one edge of the sheet and traveling together in the same 15 direction, the tapes being adapted to release the sheet when it has reached the place of deposit. To adapt the apparatus to use with varying widths of paper, I mount the tape supporting and driving rollers in side 20 frames which are adjustable toward and from the central longitudinal line of the delivery apparatus, without affecting in any way their operative connection to the actuating devices.

25 The nature of the invention is fully described below, and illustrated in the accompanying drawings, in which latter—

Figure 1 is a plan of the invention. Fig. 2 is a side elevation, Figs. 3, 4 and 5 are sections on the lines 3—3, 4—4 and 5—5 respectively, of Fig. 1. Figs. 6 and 7 are sections on the lines 6—6 and 7—7 of Fig. 3. Fig. 8 is a plan of the parts shown in Fig. 7; Fig. 9 is a detail vertical section showing 35 the head for positioning one of the tape rollers on the line 9—9, Fig. 2; and Fig. 10 is a detail view of the sheet arresting devices.

In said drawing, 10 represents the frame 40 of the press, and 11 the impression cylinder or other delivering device of the printing mechanism thereof. At each side of the path of the sheet, I arrange two endless carriers, preferably tapes, 12 and 13, one directly over the other, and support the proximate courses of these tapes in contact with each other by means of closely associated pressure rollers, so that each pair is adapted to take hold of the edge of the sheet and 45 feed it forward. The lowest tapes 13 pass around rollers 14 at one end, and rollers 15 at the other end, the shaft of rollers 14 being driven at a speed sufficient to give the tapes a speed equaling that the paper re-

ceives from the printing mechanism and in 55 the direction in which it is projected thereby. Between each pair of the rollers 14 and 15 is a series of pressure rollers 18 acting to support the upper course of the lower tapes against the lower course of the upper 60 tapes 12. The upper tapes are carried by end rollers 19 and 20 and the shaft of rollers 19 has gear 17 meshing with gear 16, so that the upper tapes are actuated at the same speed as the lower ones. The shaft 65 41 of rollers 14 may be driven in any suitable way. As shown in Figs. 1 and 5, shaft 41 has a pinion 41^a meshing with an intermediate gear 41^b driven by a gear 41^c on cylinder 11. Between the rollers 19 and 20 70 is a series of pressure rollers 22, similar to the series 18, and acting to press the lower course of the upper tapes downward. By this construction each of the tapes is opposed to another tape, so that the two can 75 grasp an edge of the passing sheets as they come from the printing mechanism and the two pairs of tapes thus seizing the sheet by its opposite edges, are enabled to control the sheet and continue its movement at 80 the surface speed of the printing mechanism until it arrives over the place at which it should be deposited.

The discharge of the sheets from the feeding tapes is accomplished in any suitable 85 way, as for instance by moving the lower tapes and their supporting rollers laterally away from under the sheet, thus withdrawing all support from it, so that it can fall without resistance, and at the same time 90 lifting the upper tapes and their rollers slightly, so as to withdraw from the sheet all the propelling power of the tapes. These changes in the tapes are brought about at the proper times by the cam 23 on shaft 24 95 actuated from the driving shaft 25, the cam swinging the pivoted lever 26 and giving longitudinal motion to a connecting rod 27, and swinging the bent lever 28 upon its pivot 29. Lever 28 is jointed to a link 21 100 attached to a collar 30 on the sliding rod 31 having racks at each end. The racks mesh with mutilated gears 33 mounted on rock shafts 34, carrying cams 35, which lift arms 36 mounted on the shafts 37 supporting the 105 driving pinions 17 actuating the rollers of the upper tapes. Arms 36 are attached to sleeves 36^a to which are attached arms 36^b

that are pivotally connected to bars 44 carrying the rollers 22, said bars 44 being thus movably supported through arms 36^b on shafts 37. By these devices when carriers 5 36 are lifted the bars 44, to which the rollers 22 are pivoted, are also raised. This operation results in freeing the sheets from the tapes so that they no longer feel any propelling force from them. Each rock shaft 10 34 also carries two peripheral cams 38 in which a stud 39 is entered, and through such studs the longitudinal bars 40 are moved outward from the paper sufficiently to carry the lower tapes from under the 15 paper, the pressure rollers 18 being pivoted to the bars and the rollers 14 and 15 being slideable upon the cross shafts 41 and 42 by which they are supported, but made to slide with the bars by guides 43 which extend 20 from the bars around their peripheries as seen at Fig. 3.

To arrest the sheet after it has been released by the tapes any suitable devices may be employed, but one construction by which 25 it may be done is the means I prefer shown in the drawing and consists of the arms 45 attached to longitudinal bars 46 and projecting over the bars 40 into the path of the paper but below the same, and co-acting 30 pivoted spring actuated triggers 47. The triggers 47 are mounted on the inner ends of rock shafts 48 passing horizontally and transversely through the bars 44 and between the rollers 22 and are provided with 35 cranks 50 on their outer ends. When the parts are in normal position the triggers are normally held above the paper by the crank 50 resting upon bars 40. The triggers are adapted to drop and clamp the paper in 40 stantly against the arms 45 under the action of springs 50^a as soon as the upper tapes are raised, as above described, and will hold the sheet until the lower tapes have been moved laterally so as to carry the inclines 45 51 on the lower tape bars 40 under the ends of crank 50 and cause them to lift the triggers. The sheet is clamped back of its transverse center so that there is very little or no tendency of the sheet to gather or 50 wrinkle back of the clamping point, the main portion of the sheet being forward of the clamps and exerting a pulling force. The clamps practically remain in action only 55 long enough to arrest the sheet and as soon as the tapes and their supports have moved back to normal positions, the clamps are held open by the cranks 50 resting on bars 40. I provide a series of openings 48^a in bars 44 allowing the arresting devices to be 60 positioned differently to accommodate sheets of different length the arms 45 being correspondingly adjustable on bars 46.

To enable the use of the invention with paper of varying widths, I form at each 65 side of the path of the paper, laterally slid-

ing heads each with a bar 46 as its backbone, and metal connections 53 from said bars 46 to the shafts 34 42 and 37, so that all parts in each head slide unitedly. And the sliding by which the heads are adjusted 70 to the paper, is accomplished by parallel transverse screws 55 mounted at each end of the apparatus and engaging the heads and operated by the crank 56, and by transmitting motion from the crank screw to the 75 corresponding screw at the other end see Fig. 1.

The feeding tapes are kept taut by providing them with a pair of tipping pivoted 80 tighteners 60 and uniting such tighteners by a spring in such manner as to render them constant in their action on the tapes.

I claim:—

1. The combination with the printing mechanism of a printing press, of a sheet 85 delivery apparatus having feeding devices and slowing devices the feeding devices whereof consists of directly opposing tapes touching the sheet only at its side edges, and the devices whereof for slowing the 90 sheet also touching only the side edges thereof, whereby danger of smearing the printed surface is obviated.

2. The combination with the printing mechanism, of sheet delivery apparatus consisting of pairs of directly opposing tapes, one pair at each side of the sheet, and gripping the proximate edges thereof, such tapes traveling in the direction of the feed, means for engaging the tail of the sheet to 100 arrest its forward movement by the tapes at the dropping point, and means for causing the tapes to release the sheet simultaneously with the arrest thereof to drop the sheet.

3. In a sheet delivery mechanism for printing presses, the combination of two opposite parallel series of rollers, and endless tapes co-acting with each series of rollers adapted to engage the outermost margins 110 of a sheet to forward the sheets from one pair of rollers to the next; with means for engaging the tail of the sheet to arrest it when released and means for causing the rollers to release the sheet at the point of 115 dropping.

4. Sheet delivery mechanism for printing presses, comprising pairs of endless carriers adapted to grip the outermost margins of the sheets between them, means engaging 120 the tail of the sheet to arrest it at the point of deposit, and means for causing the carriers to release the sheets at such point.

5. In sheet delivery mechanism for printing presses, the combination of pairs of 125 endless tapes arranged at opposite sides of the path of the sheet and adapted to engage the outermost margins of the sheet between them, means for separating the tapes to allow the sheet to drop therefrom, and 130

means adapted to engage the tail of the sheet, and arrest the sheet at the dropping point.

6. A sheet delivery mechanism for printing presses, comprising pairs of endless carriers adapted to grip only the outermost margins of a sheet between them; means arranged above and below the parallel runs of the carriers and adapted to cause them to bite the margins of the sheet therebetween, and means for separating the carriers in order to drop the sheet.

7. A sheet delivery mechanism for printing presses, comprising pairs of opposed endless carriers, means adapted to cause the parallel runs of the carriers to positively bite the margins of the sheet therebetween, and means for moving the lower carriers outward from beneath the sheet to drop it.

20 8. A sheet delivery mechanism for printing presses, comprising pairs of parallel endless carriers, means for causing the adjacent parallel runs of the carriers in each pair to positively grip the margins of a sheet lying therebetween, and means for moving the lower carriers laterally to freely drop the sheet.

9. Sheet delivery mechanism for printing presses comprising two opposite pairs of 30 endless co-acting carriers adapted to engage the outermost margins of the sheet, means for causing the parallel runs of the carriers in each pair to positively bite the margins of the sheet lying therebetween, and means for separating the carriers and moving the lower ones outward to drop the sheet.

10. In sheet delivery mechanism for printing presses, the combination of two opposed 40 parallel series of rollers adapted to engage the margins of a sheet and support and forward the same, and means for separating the series of rollers and withdrawing the lower rollers from beneath the sheet to drop it at the desired point.

11. Sheet delivery mechanism for printing presses comprising opposite pairs of co-acting endless carriers adapted to grip the outermost margins of a sheet, means for 50 stopping the sheet on such carriers when released thereby, and means for separating such carriers to freely drop the stopped sheet at the desired point.

12. Sheet delivery mechanism for printing presses comprising pairs of endless carriers arranged at opposite sides of the path of the sheet and adapted to grip only the outermost margins of the sheet between them, means for arresting the sheet on such carriers as it is released thereby, and means for separating the carriers in each pair to allow the stopped sheet to freely drop therefrom.

13. The combination with printing mechanism, of sheet delivery apparatus embody-

ing pairs of directly opposing tapes, one pair at each side of the sheet and gripping the proximate edges thereof, such tapes traveling in the direction of the feed, and being adapted to release the sheet at the point of dropping, and means for engaging the tail of the sheet to stop the sheet at the point of dropping when released by the tapes.

14. A sheet delivery mechanism for printing presses, comprising pairs of opposed 75 endless carriers arranged at opposite sides of the path of a sheet and adapted to engage the outermost margins thereof, means for causing the parallel runs of the carriers in each pair to grip the margins of the 80 sheet lying therebetween, means for arresting the sheet, and means for moving the lower carriers outward to drop the sheet.

15. A sheet delivery mechanism for printing presses, comprising pairs of endless 85 tapes adapted to receive the sheet, opposed rollers adapted to engage the parallel runs of the tapes and cause them to bite the sheet, means for stopping the sheet, and means for moving the lower carriers outward in order 90 to drop the sheet.

16. Sheet delivery mechanism for printing presses comprising a plurality of series of opposed rollers adapted to bite the outermost margins of a sheet and hold, support and 95 forward the same; with means for separating the series of rollers to release the sheet, means for simultaneously stopping the sheet, and means for thereafter withdrawing the lower series of rollers from beneath 100 the sheet.

17. In a sheet delivery mechanism for printing presses, the combination of two series of opposed co-acting rollers respectively adapted to engage the outermost 105 margins of a sheet; with means for separating the rollers vertically to cause them to freely release the sheet at the desired point, means for stopping the released sheet, and means for withdrawing the lower rollers 110 from beneath the sheet.

18. In a sheet delivery mechanism for printing presses, the combination of a series of opposed rollers adapted to engage the outermost margins of a sheet and support and 115 forward it, and endless carriers co-acting with each series of rollers, means for releasing the sheet, means for stopping the released sheet, and means for withdrawing the lower carriers from beneath the released 120 sheet.

19. In a sheet delivery mechanism for printing presses, the combination of two series of opposed co-acting rollers adapted to engage the outermost margins of a sheet and 125 support and forward it, and endless carriers co-acting with each series of rollers; with means for separating the rollers to cause them to release the sheet, means for stopping the sheet, and means for withdrawing the 130 sheet.

lower carriers from beneath the released sheet.

20. In sheet delivery mechanism for printing presses, the combination of two pairs of endless tapes adapted to engage the outermost margins of a sheet, rollers on opposite sides of the parallel runs of the tapes adapted to cause them to bite the margins of the sheet therebetween, and means for separating the rollers and tapes and for withdrawing the tapes from beneath the sheet to freely drop it.

21. In a sheet delivery mechanism for printing presses, the combination of two pairs of endless tapes adapted to grip the outermost margins of the sheet, and means for causing the parallel runs of the tapes in each pair to grip the margins of the sheet lying therebetween; with means for causing the tapes to release the sheet at the point of deposit; means for stopping the sheet at the time of its release, and means for withdrawing the lower tapes from beneath the released sheet.

22. In a sheet delivery mechanism for printing presses the combination of pairs of endless tapes arranged at opposite sides of the path of the sheet, and adapted to engage the outermost margins of the sheet between them; with means for directly separating the tapes to release the sheet, and means for moving the lower sets of tapes from beneath the released sheet.

23. In a sheet delivery mechanism for printing presses, the combination of pairs of endless tapes arranged at opposite sides of the path of the sheet and adapted to engage the outermost margins of the sheet between them, and presser rollers co-acting with the pairs of tapes to cause them to bite the sheets; with means for directly separating the tapes to release the sheet, and means for moving the lower set of tapes from beneath the released sheet.

CARL HENDERSON.
